UNITED STATES PATENT OFFICE.

CHARLES W. McDANIEL, OF KANSAS CITY, MISSOURI.

FIRE-ALARM SYSTEM.

No. 870,574.

Specification of Letters Patent.

Patented Nov. 12, 1907.

Application filed April 23, 1906. Serial No. 313,175.

To all whom it may concern:

Be it known that I, CHARLES W. McDANIEL, a citizen of the United States, residing at Kansas City, in the county of Jackson and State of Missouri, have invented 5 a certain new and useful Improvement in Fire-Alarm Systems, of which the following is a full, clear, concise, and exact description, reference being had to the accompanying drawings, forming a part of this specification.

10 My invention relates to alarm systems, particularly to a system adapted for association with a telephone system.

In my system an ordinary rheotome bell is included in a circuit controlled by thermostat devices which 15 upon being heated to a predetermined degree cause closure of the circuit and actuation of the alarm bell. In the circuit I also include a primary winding of an electromagnet which also has a secondary winding, whose one terminal connects with the front contact 20 of an armature, which armature and the other terminal of the secondary winding connect with the telephone line limbs leading to the telephone central exchange. The adjustment is such that when the alarm bell circuit is closed the secondary circuit will also be closed 25 to cause actuation of the indicating signal at the central exchange. The alarm bell will serve to notify the inhabitants or watchman of the premises if they are present. The central operator upon receiving the signal connects her cord circuit with the line in the usual 30 manner and connects in her operator's set. The secondary winding is of such adjustment that a humming noise will be produced in the operator's ear piece which immediately notifies her that the alarm circuit at the subscriber's station has been actuated. If the inhabitants 35 or watchman, when the alarm is actuated, are absent, central can then take steps to find them to notify them of the fact. Under normal conditions, however, this alarm circuit is entirely independent of the telephone system.

40 My invention will be best understood by reference to the accompanying drawings, wherein I have diagrammatically illustrated an alarm circuit and a telephone circuit leading to a central exchange.

In the limbs *a*—*b* of the alarm circuit are included a 45 battery 1, the primary winding 2 of an electromagnet 3 and the alarm bell 4. The thermostat devices 5—5—5 are normally open and arranged in multiple between the line limbs. When one or more of these thermostat devices are heated beyond a certain degree, as in 50 case of fire in their vicinity, they are affected to close the alarm circuit and the alarm bell armature 6 is vibrated to ring the bell and to repeatedly open the circuit in the well known manner. On the electromagnet 3 is also a secondary winding 7, whose one terminal connects 55 with the first contact 8. The other terminal of this secondary winding and the armature 9 for the electro-

magnet connect through conductors 10 and 11, respectively, with binding posts 12 and 13 of the telephone line T, whose limbs 14 and 15 extend to the central exchange C. At the central exchange any well known 60 telephonic mechanism may be employed and I have shown a line relay 16 engaged by the windings 17 and 18 in the line limbs 14 and 15, respectively, the common source of current 19 being normally in bridge of the line limbs. The line relay armature 20 controls 65 the local circuit for the indicating lamp 21. A spring-jack 22 is connected across the line limbs and adapted for connection with a plug 23 connected with the cord circuit c. In the cord circuit is the usual operator's key *k* adapted when actuated in one direction to connect with the cord strands the operator's telephone set 0, and when actuated in the other direction to connect with the cord strands the generator *g*. At the same 70 station is the ordinary telephonic apparatus comprising the transmitter 24, primary winding 25, the receiver hook 26, secondary winding 27 and the receiver 28 normally in place on the hook, the circuit through the receiver circuit being normally closed. A signal bell 29 in series with a condenser 30 is normally connected between the line limb 14 and through the receiver hook with the line limb 15.

75 The operation of the system is now apparent. Under ordinary circumstances, the telephone and alarm systems are entirely independent of each other as the secondary-circuit including the secondary winding is 80 normally open as the armature 9 is normally out of engagement with the contact 8. Upon actuation of a thermostat device, however, the alarm circuit becomes affected, as before stated, and is repeatedly opened and closed upon vibration of the armature 6 into and 85 out of engagement with its contact 6'. Interrupted current therefore flows through the primary winding 2 of the electromagnet. This electromagnet immediately becomes energized to attract the armature 9 into engagement with the contact 8, thereby closing a secondary circuit through the line limbs, through the indicating relay windings and through the source of current at the central exchange. The line relay becomes 90 energized and the line lamp 21 illuminated in answer to which the operator inserts the plug 23 into the 95 springjack and actuates her key to connect her operator's set in circuit in anticipation of a call from the subscriber. The secondary winding of the electromagnet, however, is of high resistance and the alternating current induced therein from the primary circuit causes a humming noise in the operator's receiver 100 which informs her that the alarm circuit is effective. If the inhabitants or watchman are present they will hear the alarm and will be notified of the danger. The central operator, upon receiving the alarm will 105 actuate her key to connect the generator *g* with the line to send signaling current to the signal bell 29 at the

substation to assist in arousing the inhabitants or the watchman. If any one is near the telephone will be answered and central knows that the danger has been discovered. A switch 31 may be included in the secondary circuit at the telephone to remove the buzzing noise and to allow conversation. If no one is near, the central operator will get no answer over the telephone and she can then notify the proper persons that the alarm circuit connected with a certain line has been actuated. The thermostat devices may be remote from the alarm bell and telephone, and the telephone also, need not be in the same building with the alarm bell or thermostat devices, but may be remote therefrom, as for instance, the alarm circuit 15 might be in a factory to arouse the watchman in case of fire or other danger, and the telephone may be at the owner's house. The watchman and the central exchange would be notified immediately upon actuation of the alarm circuit and the central operator can 20 then ring the telephone to notify the owner. The electromagnet and its windings may also be given various adjustments. The armature 9 may be sluggish to be retained in its attracted position by the efforts of the primary winding alone. The adjustment 25 may also be such that when the armature is first attracted the secondary circuit, including the secondary winding and the central supply source, will be closed to maintain energization of the electromagnet and the armature again released upon opening of the secondary circuit by switch 31. Many other arrangements and adjustments will also suggest themselves without departing from the scope or spirit of the invention. I do not, therefore, wish to be limited to the arrangement shown.

35 I claim as new, however, and desire to secure by Letters Patent:

1. In a combined alarm and telephone system, the combination with a telephone line leading from a substation to a central exchange, of an alarm circuit at the substation, a source of direct current and a rheostatic alarm bell for said alarm circuit, a thermostatic mechanism for controlling the alarm circuit, an electromagnet having a primary winding included in said alarm circuit, a secondary winding for the electromagnet adapted for connection with the telephone line, the armature of said electromagnet being normally disposed to open the secondary circuit, and signaling apparatus and a source of current at the central exchange, actuation of the alarm circuit causing actuation of the electromagnet to close the secondary circuit, whereupon induced current will flow through the secondary circuit and the telephone line to cause actuation of the signaling apparatus at the central exchange.
- 40 45 50

2. In a combined alarm and telephone system, the combination with a telephone line leading from a substation to a central exchange, of an alarm circuit at the substation, a source of current and a rheotome alarm bell for the alarm circuit, thermostat controlling means for the alarm circuit, an electromagnet having a primary winding included in the alarm circuit, a secondary winding for the electromagnet, one terminal of the secondary winding being connected with one of the line limbs, the other terminal of the secondary winding being adapted for connection with the other line limb upon actuation of the electromagnet armature, signalling apparatus and a source of current at the central exchange, and operator's telephone apparatus at the central exchange adapted for connection with the telephone line, actuation of the alarm circuit causing actuation of the electromagnet armature to close the secondary circuit, whereby the signalling apparatus at the central exchange is actuated and whereby current flow is induced in the secondary circuit to cause the noise in

the operator's telephonic apparatus upon connection thereof with the telephone line in response to the signalling apparatus.

3. In an alarm system, the combination of a main alarm circuit, a source of current and an alarm apparatus in said circuit, circuit controlling means for the alarm circuit, an electromagnet having a winding included in said alarm circuit, a secondary winding for said electromagnet, an auxiliary alarm circuit adapted to include said secondary winding but normally held open by the armature of the electromagnet, and alarm or signaling mechanism in said auxiliary circuit, actuation of the main alarm circuit causing first closure of the auxiliary alarm circuit and then induction of current flow therein to actuate the alarm mechanism connected therewith. 85

4. In an alarm system, the combination with a main alarm circuit having a source of current and alarm mechanism, an electromagnet having a primary winding included in the alarm circuit, a secondary winding for the electromagnet in inductive relation with the primary winding, a secondary alarm circuit adapted to include the secondary winding upon actuation of the electromagnet armature when the alarm circuit is actuated, a source of current for the secondary circuit, and alarm apparatus for the secondary circuit, actuation of the main alarm circuit causing attraction of the electromagnet armature to close the secondary circuit whereby the source of current in said secondary circuit supplies current through the secondary winding to maintain actuation of the electromagnet armature, said secondary circuit then receiving induced current from the primary winding, which induced current causes actuation of the alarm mechanism connected with the secondary circuit. 90 95 100

5. In an alarm system, the combination with a main alarm circuit having a source of current and a rheostome bell, an electromagnet having a primary winding included in the alarm circuit, a secondary winding for the electromagnet in inductive relation with the primary winding, a secondary alarm circuit adapted to include the secondary winding upon actuation of the electromagnet armature when the alarm circuit is actuated, a source of current for the secondary circuit, and alarm mechanism for the secondary circuit, actuation of the main alarm circuit causing attraction of the electromagnet armature to close the secondary circuit whereby the source of current in said secondary circuit supplies current through the secondary winding to maintain actuation of the electromagnet armature, said secondary circuit then receiving induced current from the primary winding, which induced current causes actuation of the alarm mechanism when connected with the secondary circuit. 120

6. In an alarm system, the combination of a main alarm circuit, a source of current and an alarm apparatus in said circuit, thermostatic controlling mechanism for the alarm circuit, an electromagnet having a primary winding included in said alarm circuit, a secondary winding for said electromagnet, an auxiliary alarm circuit adapted to include said secondary winding but normally held open by the armature of the electromagnet, and alarm or signaling mechanism in said auxiliary circuit, actuation of the main alarm circuit causing first closure of the auxiliary alarm circuit and then induction of current flow therein to actuate the alarm mechanism connected therewith.

7. In an alarm system, the combination of a main alarm circuit having a source of current and alarm mechanism, thermostatic controlling devices in said main alarm circuit, an electromagnet having a primary winding included in the alarm circuit, a secondary winding for the electromagnet in inductive relation with the primary winding, a secondary alarm circuit adapted to include the secondary circuit upon actuation of the electromagnet armature when the alarm circuit is actuated, a source of current for the secondary current, and alarm mechanism for the secondary circuit, actuation of the main alarm circuit causing attraction of the electromagnet armature to close the secondary circuit, whereby the source of current in said secondary circuit supplies current through the secondary winding to maintain actuation of the electromagnet armature, said secondary circuit then receiving induced current from the primary winding, which current causes

actuation of the alarm mechanism when connected with the secondary circuit.

8. In an alarm system, the combination of a main alarm circuit, a source of current and a rheotome bell in said circuit, a thermostatic mechanism for controlling the alarm circuit, an electromagnet having a primary winding included in said alarm circuit, a secondary winding for said electromagnet, an auxiliary alarm circuit adapted to include said secondary winding upon actuation of the electromagnet armature when the alarm circuit is actuated, a source of current for the secondary circuit, and alarm apparatus for the secondary circuit, actuation of the main alarm circuit causing attraction of the electromagnet

armature to close the secondary circuit whereby the source of current in said secondary circuit supplies current through the secondary winding to maintain actuation of the electromagnet armature, said secondary circuit then receiving induced current from the primary winding, which induced current causes actuation of the alarm mechanism connected with the secondary circuit.

20

In witness whereof I hereunto subscribe my name this 13th day of April A. D., 1908.
